UNITED STATES PATENT OFFICE.

JOSEPH PANSY, OF CENTRAL FALLS, RHODE ISLAND, ASSIGNOR TO CROMPTON & KNOWLES LOOM WORKS, OF WORCESTER, MASSACHUSETTS, A CORPORATION OF MASSACHUSETTS.

PROTECTION MECHANISM FOR LOOMS.

Application filed March 26, 1927. Serial No. 178,716.

This invention relates to protector mechanism for looms and it is the general object of the invention to provide means for throwing off the power and applying the brake 5 before the lay is stopped abruptly by the bunter without lessening the time allowed for the flight of the shuttle.

The usual protector mechanism employs a rolling rod mounted on the lay and having 10 at least one forwardly projecting dagger. Fingers secured to the rod engage the shuttle binders and when the shuttle is properly boxed the rod will roll to move the dagger out of the path of a bunter fixed to the loom 15 frame. As generally employed the effect of the protection is to throw off the shipper handle and apply the brake at the same time that the dagger engages the bunter to stop the motion of the lay. With this arrangement 20 it is found that in heavy or fast running looms the power is actually on when the dagger engages the bunter. The reason for this is that the lock depended upon to hold the shipper handle in running position 25 acts something like a toggle lock in that the last part of the movement of the shipper handle merely locks the latter in position, the power having been put on completely a short time prior to the end of the movement 30 of the shipper handle. As a result of this when the handle is being knocked off it must be brought back an appreciable distance to effect unlocking before it is able to throw off the power. During this short interval 35 the drive for the loom is slightly tighter than normal and it is found that when the lay strikes the fixed bunter the power is still on.

It is an important feature of my present 40 invention to provide means whereby the brake may be applied before the dagger engages the bunter without shortening the time allowed for the flight of the shuttle. I am aware that devices have been proposed here- 45 tofore for applying the brake before the dagger engages the bunter, but in each of these instances the mechanism is so operated as to shorten the time available for the passage of the shuttle. In the cycle of 50 the pick the flight of the shuttle will ordinarily occupy the time lapsing between picking and protection. The speed at which a loom may be run is determined very largely upon this interval of time and as a result 55 loom fixers customarily adjust the various

parts of the loom so as to take full advantage of the time allowed the shuttle to pass through the shed. Any mechanism, therefore, which lessens the time allowed to the flight of the shuttle would cut down the 60 speed of the loom.

It is a more detailed object of my invention to provide a pair of daggers each effective to stop the loom, one being the usual dagger which works with the bunter to 65 cause the sudden stopping of the lay, and the other being an auxiliary dagger operative to throw off the brake and shipper handle prior to the operation of the main dagger. As set forth herein these daggers 70 maintain a fixed angular relation and when the main dagger starts to move so as to clear its bunter the auxiliary dagger will also start to move, but because the latter is light it can clear its bunter in less time 75 than the main dagger can clear its bunter. For this reason the auxiliary bunter, when not moving to clear its bunter, can set the brakes before the main dagger engages its bunter. 80

With these and other objects which will appear as the description proceeds, my invention relates to the arrangements and combinations of parts hereinafter set forth, and more particularly pointed out in the 85 claims.

In the accompanying drawings, wherein a convenient embodiment of my invention is shown,

Fig. 1 is a top plan view of a portion of 90 the loom having my improvements applied thereto,

Fig. 2 is a vertical section on line 2—2 of Fig. 1 and showing the parts in normal 95 running position,

Fig. 3 is a fragmental view of a portion of Fig. 2 showing the shipper and brake handles in non-running position,

Figs. 4, 5 and 6 are enlarged sections on line 4—4 of Fig. 1 showing the parts in different positions, 100

Fig. 7 is an enlarged horizontal section on line 7—7 of Fig. 2,

Fig. 8 is a diagrammatic view showing the relation of the two daggers and the parts 105 with which they cooperate to effect stopping of the loom, and

Fig. 9 is a detailed vertical section on line 9—9 of Fig. 1.

In the drawings I have shown the inven- 110

tion as applied to a loom having a center filling stop motion and have applied my auxiliary parts to the rolling rod of the protector mechanism and the bar of the filling stop motion. In Figs. 1 and 2 I have indicated the loom frame 10 having a breast beam 11 and a crank shaft 12. The crank shaft may be driven in any approved manner but I have shown herein a form of drive usual for 10 silk looms, the same comprising a motor 13 having a pinion 14 which meshes with a gear 15. Said gear is provided with a grooved sleeve 16 to cooperate with the forked end of a shipper lever 17 pivoted as at 18 to a 15 bracket 19 supported by the loom frame. A friction disk 20 is keyed to the shaft 12 and has a friction surface 21 to cooperate with a corresponding friction surface 22 formed on the inner face of the gear 15. A shoulder 23 20 fastened to the crank shaft 12 limits end-wise movement of the disk 20.

The shipper lever 17 extends forwardly and is provided with an upstanding stud 24 which is received by an oblique cam slot 25 formed on the lower end of a shipper handle 26 pivoted to the loom frame as at 27. When the shipper handle is in the position shown in Fig. 2 the cam slot and stud are so related as to move the gear 15 against 30 the disk 20 and cause turning of crank shaft 12 by motor 13.

The brake motion includes a relatively heavy lever 27^a pivoted as at 28 to the rear part of the loom frame and being connected as at 29 by means of an adjustable connector 30 to a flexible friction band 31, the forward end of which is anchored to the loom frame as at 32. A heavy tension spring 33 is interposed between the lever 27^a and a fixed 40 lug 34 by means of an adjustable connector 35. A forwardly extending rod 36 is pivotally connected at the rear end thereof to the lever 27^a at 37 while the forward end thereof is connected as at 38 to a lever 39 rotatable about the shipper shaft 27. A brake handle 40 is secured to rocking bar 41 forming part of the center stop motion and said handle 40 is provided with two notches of different depths, both of which are proportioned to receive a roller 42 mounted on the lever 39. The high notch 43 receives said roller while the loom is running and tends to hold the rod 36 in rearward position thus lifting the flexible strap 31 off the brake 55 wheel 44 which is fastened to the crank shaft 12. The low notch 45 receives the roller when the brake is to be applied.

The protector mechanism may be of the usual form and comprises a protector rod 60 46 pivotally mounted to the lay L and having protector fingers 47 one of which is shown in the drawings. Each finger cooperates with a binder 48 the position of which is determined by shuttle S and said rod 46 is 65 provided with two forwardly projecting rel-

atively heavy daggers 49 only one of which is shown in Fig. 1. A torsion spring 50 lies around the protector rod 46 and has one end extended under the lay as at 51 and the other end under the dagger 49 and the effect of said spring is to raise the dagger. 70

The parts for cooperating with the heavy dagger 49 are shown in detail in Figs. 6 and 7, where it will be seen that a bunter lever 52 is pivoted as at 53 to the underside of the 75 breast beam 11. Said bunter lever has an inwardly projecting portion which lies opposite a shock absorber 54 which may be a pad of rubber and the outer end of said lever extends in front of the brake handle 40 so and a lug 55 fastened with the shipper handle 26. Said bunter lever is provided with a notch 56 as shown in Figs. 4, 5 and 6 and because of the work which must be done by said bunter lever, it must be of substantial proportions. The under side of the breast beam may be provided with a guide plate 57 having a rearwardly and upwardly inclined lower face 58 which may guide the dagger 49 toward the notch 56 when a shuttle 90 is properly boxed.

The rocking bar 41 is pivoted in bearings 60 on the under side of the breast beam and has a downwardly extending offset 61 for the dagger 49. Said rocking bar cooperates 95 with the filling stop motion, which is of the usual construction, and serves when rocked in a right hand direction as viewed in Figs. 2 and 4 to move the roller 42 from the high dwell 43 to the low dwell 45, thereby applying the brake 31.

The mechanism thus far described is of common construction and as such forms no part of my present invention.

In carrying my improvements into effect 105 I provide an auxiliary dagger to be moved with the main dagger on the protector rod 46, and I further provide a bunter mounted on the rocking bar 41, of the filling stop motion and so arrange and proportion said 110 parts that they will apply brake 31 before dagger 49 engages bunter lever 52. Accordingly, I secure to the protector rod 46 a holder 70 made in two parts as shown in Fig. 9, screw 71 fastening the parts together and 115 clamping them tightly on to the rod 46. A comparatively light dagger 72 is secured into said holder 70 and has a forwardly projecting dagger end 73 which is not so blunt as the corresponding end of the main dagger 120 49. Furthermore, I provide a bunter 74 which is secured to the rocking bar 41 by means of set screw 75. Said bunter has formed on the lower portion thereof a small 125 notch 76 and that portion of the bunter lying above the notch extends rearwardly almost in a straight line for a short distance so as to engage the top of the auxiliary dagger when said bunter is engaged by the latter and is rolled thereby to discon- 130

nect the dagger and bunter. The notch 76 is not as deep as the notch 56 on the bunter lever.

In the operation of the loom the lay L moves backwardly and forwardly, the shuttle S being picked when the lay is half way back or on so-called top center and arriving on one of the boxes approximately half a pick later. As the shuttle is boxed the main 5 dagger 49 will be depressed and as the lay advances the bunter lever will remain in the position shown in Fig. 7, being unengaged by the main dagger. The operation of the main dagger in moving clear of the bunter lever is set forth diagrammatically in Fig. 10 15 20 25 30 35 40 45 50 55 60 65 70 75 80 85 90 95 100 105 110 115 120 125 lever is set forth diagrammatically in Fig. 8, where the dotted line 100 indicates the path followed by the point of the dagger 49 when the shuttle is properly boxed and wherein the full curve line 101 indicates the path followed by the dagger 49 when it is to engage the notch 56.

When the lay has moved forwardly a sufficient distance for the main dagger 49 to arrive at point 102 indicated in Fig. 8 and 25 for the auxiliary dagger 72 to arrive at point 103, said daggers will begin to take one or the other of the courses indicated in full and dotted curved lines, 100, 101, 104 and 105 in said figure.

30 The upper solid curved line 104 indicates the path to be followed by the auxiliary dagger when the shuttle is improperly boxed, whereas the lower dotted curved line 105 indicates the path to be followed when 35 the shuttle is boxed properly. Because of the fact that both bunters are secured to the same rod full lines 101 and 104 will be concentric with the center of the lay and the dotted lines 100 and 105 will be generated 40 by two points which are a fixed distance apart and moving forwardly with the lay. These curves in dotted lines will not be concentric with the center of the lay because they are produced by a combining of the 45 rocking movement of the protector rod with the forward movement of the lay.

The notch 76 is so shallow that it requires but a small movement on the part of the auxiliary dagger to clear it so that a 50 comparatively short travel only beyond the point 103 as shown in Fig. 8, is necessary to have the auxiliary lever clear the bunter 74. The notch in the bunter lever 52, however, being larger, must be spaced farther from 55 the point 102 in order to give the main dagger sufficient time to move downwardly to clear said notch. Because of the relation described in connection with Fig. 8 it is possible for the light dagger to start angular 60 movement of the rocking bar 41 before the main dagger engages the bunter lever. This result is accomplished without taking any time from the flight of the shuttle.

From the foregoing it will be seen that I 65 have provided a very simple means for

throwing off the power and applying the brake of a loom prior to stopping of the lay by the protector mechanism, and that this result is accomplished without lessening the time allowed for the flight of the shuttle.

Furthermore, it will be seen that the main 70 part of the protector mechanism is of usual construction so that the auxiliary devices may be added to looms already built.

Having thus described my invention it 75 will be apparent that changes and modifications may be made therein by those skilled in the art without departing from the spirit and scope of the invention, and I do not 80 wish to be limited to the details herein disclosed but what I claim is:

1. In stopping mechanism for a loom having a lay and a shuttle, shipper and brake mechanism, a protector rod movably mounted on the lay and controlled as to angular 85 position relatively to the lay by the shuttle, a main dagger and an auxiliary dagger both secured to the protector rod and moving with the latter in fixed angular position, a main bunter to cooperate with main dagger 90 to effect sudden stoppage of the loom, a rolling rod mounted on a fixed part of the loom and extending substantially parallel to the protector rod, an auxiliary bunter secured to the rolling rod to cooperate with the auxiliary dagger to operate the shipper and brake mechanism, said auxiliary dagger 95 cooperating with the auxiliary bunter to effect angular movement of the rolling rod on the forward movement of the lay prior 100 to the engagement of the main bunter and main dagger.

2. In stopping mechanism for a loom having a lay and a shuttle, shipper and brake mechanism, a protector rod movably 105 mounted on the lay and controlled as to angular position relatively to the lay by the shuttle, a main dagger and an auxiliary dagger both secured to the protector rod and moving with the latter in fixed angular position, a main bunter to cooperate with main dagger to effect sudden stoppage of the loom, a rolling rod mounted on a fixed part of the loom and extending substantially parallel to the protector rod, an auxiliary bunter secured to the rolling rod to 110 cooperate with the auxiliary dagger to operate the shipper and brake mechanism, said auxiliary dagger cooperating with the auxiliary bunter to effect angular movement of the rolling rod on the forward movement of the lay prior 115 to the engagement of the main bunter and main dagger, the main and auxiliary bunters each having a notch to receive the corresponding dagger, the notch in the main bunter being larger than the notch in the auxiliary bunter.

In testimony whereof I have hereunto affixed my signature.

JOSEPH PANSY.
